UNITED STATES PATENT OFFICE.

JAMES L. SMITH, OF PRINCETON, INDIANA.

PORTABLE SEAT.

SPECIFICATION forming part of Letters Patent No. 699,932, dated May 13, 1902.

Application filed February 25, 1901. Serial No. 48,830. (No model.)

To all whom it may concern:

Be it known that I, JAMES L. SMITH, a citizen of the United States, residing at Princeton, in the county of Gibson and State of Indiana, have invented a new and useful Portable Seat, of which the following is a specification.

The invention relates to improvements in portable seats.

10 The object of the present invention is to improve the construction of portable seats and to provide a simple and comparatively inexpensive one designed more especially for affording a seat or rest for a person while 15 working and adapted to be readily attached to and carried by the wearer and capable of being readily adjusted to arrange it in the proper position and at the proper height to suit the character of the work to be performed 20 by the wearer.

The invention consists in the construction and novel combination and arrangement of parts hereinafter fully described, illustrated in the accompanying drawings, and pointed 25 out in the claims hereto appended.

In the drawings, Figure 1 is a perspective view of a portable seat constructed in accordance with this invention and shown arranged for use. Fig. 2 is a similar view, 30 the seat being folded. Fig. 3 is an enlarged detail sectional view illustrating the construction of the leg and showing the manner of connecting the same to the seat. Fig. 4 is a similar view taken at right angles to Fig. 3.

35 Like numerals of reference designate corresponding parts in all the figures of the drawings.

1 designates a seat curved transversely and presenting a concave upper face and provided 40 with curved arms 2, extending upward from the seat when the latter is arranged in the position illustrated in Fig. 1 of the drawings, and the said arms are pivoted at their upper ends to a belt 4 by pivots 5. The belt, 45 which is preferably constructed of leather, is provided with a buckle, and the arms are preferably constructed of a single piece of metal secured to the lower face of the seat and curved, as clearly illustrated in Fig. 2 of 50 the accompanying drawings. By constructing the seat and the arms in this manner they are adapted to conform generally to the

configuration of the body of the wearer both when the seat is arranged for use and when it is swung upward to fold it out of the way. 55 The belt is adapted to be arranged around the waist of the wearer, and the arms are located at opposite sides of the wearer when the seat is arranged as shown in Fig. 1; but the belt may be shifted slightly to bring the 60 seat slightly to one side to form a hip-support for affording a rest for a person while he is in practically a standing position.

The seat is provided with a pair of depending ears 6, having inner and outer or upper 65 and lower transverse fastening devices 7 and 8 and preferably constructed of a single piece of metal bent into approximately U shape; but the ears may be constructed in any other suitable manner. The ears 6 receive the upper end of a leg 9, which is provided at its top with recesses 10, preferably formed by a transverse series of teeth forming a toothed head for engaging the upper fastening device 7 for holding the leg at the 70 desired angle; but instead of providing a fastening device for engagement with the teeth of the upper end or head of the leg the seat may be provided with any other suitable means for effecting this result. The lower 75 or outer fastening device 8 is arranged in a longitudinal slot 11 of the leg, and this slot 80 permits the necessary longitudinal movement of the leg to engage its upper end with the upper fastening device 7 and to 85 disengage it therefrom. Any number of teeth or recesses 10 may be provided to secure the necessary adjustment or angular disposition of the leg with relation to the seat, and when the leg is engaged with the 90 upper fastening device, as illustrated in Fig. 3 of the accompanying drawings, it is retained in such position by a wedge-shaped key 12. The wedge-shaped key 12, which is interposed between the fastening device 8 and the outer 95 or upper end wall of the slot, forms an efficient locking device for holding the upper fastening device 7 in one of the teeth or recesses 10. The chain is adapted to be readily grasped by the operator in withdrawing the wedge-shaped key; but any other suitable flexible connection may be employed for securing the key to the leg. 100

The leg in the accompanying drawings is

shown composed of upper and lower telescoping sections 14 and 15, and the fastening devices 7 and 8 are shown as rivets. The upper section 14 of the leg is tubular and receives the lower section, which is adapted to be moved inward and outward to vary the length of the leg for raising and lowering the seat. The leg is secured at the desired adjustment by a clamping - screw 16, mounted in a threaded perforation of the upper section and engaging the lower section.

The lower fastening device 8 forms a pivot for the leg, which is adapted to swing in either direction to position it with relation to the seat and also to fold the device. The leg is adapted to be folded, as illustrated in Fig. 2 of the drawings, to swing the seat upward for folding the latter, and the said leg is provided with an eye 17, which is engaged by a snap-hook 18, mounted on the belt at the back thereof and adapted to be readily engaged with and disengaged from the said eye 17. The leg may be turned in the opposite direction to fold the device; but the seat will be brought to a higher position on the back of a person by folding it as illustrated in Fig. 2.

Instead of attaching the seat to the wearer by means of a leather belt any other suitable means may be employed for this purpose. The lower fastening device may be provided with a sleeve 19, having its lower face flush with the lower edges of the ears and adapted to be engaged by the wedge-shaped key; but any other construction may be provided for enabling the wedge to engage the pivot.

The portable seat, which is especially adapted for the convenience of persons while working, is capable of being readily arranged to afford a seat of the desired elevation to permit a person to sit while milking or picking cotton, berries, and the like, and the leg is adapted to be extended and placed against the hip to provide a hip-rest for supporting a person while in an upright or substantially upright position while working at a lathe, bench, or the like. The leg is also adapted to be arranged at different angles to position it properly with relation to the seat to afford the desired support, and it will be apparent that the device will be found of great advantage to persons of all occupations. When the leg is folded, it may be conveniently carried, and when it is not folded it will not come in contact with the ground or floor or materially interfere with the movements of the wearer, as the said leg is designed to be of a length less than the length of the legs of the person using it. The portable seat is adapted for both males and females, and after it has been adjusted to the person it will not require attention, and such person will have the free use of both hands in whatever labor he may be employed.

What I claim is—

1. A device of the class described comprising a seat, a leg pivotally connected at a point between its ends with the seat and adapted

to be arranged at different angles, and means for detachably connecting the upper end of the leg with the seat, whereby the leg is rigidly held in its adjusted position, substantially as described. 70

2. A device of the class described comprising a seat, a leg pivotally and slidably connected at a point between its ends with the seat and adapted to be arranged at different angles, and means for detachably interlocking the upper end of the leg with the seat, whereby when the leg is drawn outward, it will be disengaged from the seat, and when moved inward will be engaged with the same, substantially as described. 75 80

3. A device of the class described comprising a seat provided at opposite sides with arms, a belt having the arms pivotally connected to it, a folding leg pivotally connected with the seat, and means for connecting the leg to the belt, whereby the leg and the seat are retained in their folded positions, substantially as described. 85 90

4. A device of the class described comprising a seat designed to be connected to a person, and a folding leg pivotally and slidably connected near one end with the seat and adapted to be arranged at different angles 95 and having an interlocking connection with the seat, whereby it is held rigidly with the same, substantially as described.

5. A device of the class described comprising a seat, a folding leg pivotally connected 100 between its ends with the seat and interlocked with the same, said leg being capable of a limited longitudinal movement, whereby it is engaged with and disengaged from the seat, and a fastening device for holding the leg 105 against such longitudinal movement, substantially as and for the purpose described.

6. A device of the class described comprising a seat designed to be connected to and carried by a person, a leg provided at its upper end with teeth and having a slot, a pivot carried by the seat and connected with the same and arranged in the said slot, and means carried by the seat and co-operating with the teeth of the leg, whereby the seat and the leg 115 are interlocked, substantially as described.

7. A device of the class described comprising a seat provided with ears, a leg having a slot and arranged between the ears and provided with recesses, inner and outer fastening devices carried by the ears, the outer fastening device being arranged in the slot of the leg and the inner fastening device being arranged to fit in the said recesses, a key adapted to lock the leg against movement, and means for securing the seat to a person, substantially as described. 120 125

In testimony that I claim the foregoing as my own I have hereto affixed my signature in the presence of two witnesses.

JAMES L. SMITH.
